United States Patent Office.

LEVI RICHARDS, OF PROVIDENCE, RHODE ISLAND, ASSIGNOR TO HIMSELF,
THOMAS R. RATHBUN, AND CHARLES I. RICHARDS, OF THE SAME PLACE.

Letters Patent No. 60,939, dated January 1, 1867.

IMPROVEMENTS IN MACHINES FOR MAKING EYELETS.

The Schedule referred to in these Letters Patent and making part of the same.

TO ALL WHOM IT MAY CONCERN:

Be it known that I, LEVI RICHARDS, of Providence, in the county of Providence, and State of Rhode Island, have invented a new and improved Machine for Making Eyelets; and I do hereby declare that the following is a full, clear, and exact description thereof, which will enable others skilled in the art to make and use the same, reference being had to the accompanying drawings, forming part of this specification, in which—

Figure 1 is a side sectional view of my invention, taken in the line $x x$, fig. 3.

Figure 2, a front view of the same.

Figure 3, a plan or top view of the same.

Figure 4, a view of a finished eyelet.

Figure 5, a view of a partially completed eyelet.

Similar letters of reference indicate like parts.

This invention relates to a new and improved machine for making metallic eyelets; and it consists of a cutter and dies arranged and operated in such a manner that they will cut the plate in circular form and swage it into cup or tube shape. The invention also consists of a conveyer or carrier for taking the cup or tube from the dies above mentioned and conveying it to a second pair of dies operating in connection with a punch, and in such a manner that the cup or tube formed by the first pair of dies will be swaged into proper form and punched, so as to complete the eyelet.

A represents a base or bed plate on which the working parts of the machine are placed or secured, and B is a driving-shaft, the bearings of which are in uprights a , on the base or bed plate A. On this driving-shaft there are two cranks or eccentrics, to which pitmen C C are attached by metal straps $a' a'$. The cranks or eccentrics above named coincide with each other in position, and the outer ends of the pitmen C C are connected by pivot bolts b to a head, c , at the inner end of a tube, D, which is allowed to slide freely in bearings in uprights $d d$, on the base or bed plate A, the cranks or eccentrics and the pitmen giving a reciprocating movement to the tube D. The outer end, e , of this tube D, is a circular cutter, its edge being angular or sharp; and said cutter, each time the tube D is shoved forward, works in a circular hole, f , made in an upright plate or bar, E, on the base A, as shown clearly in fig. 3, and a hole, g , smaller in diameter than f , is made entirely through the plate or bar E, concentric with f , the hole g being of slightly taper form. Within the tube D there is fitted a plunger, F, which is allowed to slide freely in D, and is operated by a yoke, G, through which a wrist pin, h , passes, said pin being secured eccentrically between two wheels or circular heads, $i i$, on the shaft B. The pin h and the cranks or eccentrics which operate the pitmen C C have such a relative position with each other that the tube D will be forced forward to its fullest extent into the hole f before the plunger F is moved out of D, and the latter, at the completion of the forward movement of tube D, moved forward so as to pass entirely through the hole g . By this arrangement it will be seen that if a piece of sheet metal is placed over the hole f the tube D will, as it is moved against the plate and enters f , cut said plate in circular form and press to the inner end of hole f , and the plunger F, in moving forward and out of tube D, will force the circular piece of metal through the hole g , and thereby swage it into tube or cup shape, as shown at h , in fig. 5. This completes the first process of the operation of my machine. H represents what I term a conveyer or carrier, which is simply a metal bar constructed with two jaws, $i i$, curved at their ends to form a circular chamber, i^* , to receive the tubes or cups h as they are forced out from the holes g . This conveyer or carrier is attached to a slide, I, which works between suitable guides $j j$, and is operated by a lever J, to which motion is given by a cam, K, on the driving-shaft B. The chamber i^* is in line with the hole g at the outer side of the plate or bar E, when the plunger F forces the tube or cup h through the hole g , the chamber i^* receiving the tube or cup, as shown in fig. 3, the conveyer or carrier, after the plunger F is drawn back, being moved from the plate or bar E back towards a similar plate or bar, L, on the base A, so that the chamber i^* of the conveyer or carrier will be brought in line with a hole, k , in the plate or bar L, which forms a female die and has its front end made of flaring form, as shown at l , in fig. 3. M is a sliding rod, which has its bearing in one of the same uprights, $d d$, as the tube D. This rod M is operated by a pitman, m, from a crank on the shaft B, and the rod M has a plunger or punch, N, attached to it, which works loosely in a tube, O, having

its bearing in the other upright, *d*. On the rear end of the tube *O* there is fitted a cylindrical socket, *P*, in which the front end of the rod *M* works, and a spiral spring, *Q*, is placed on the socket *P*, one end of said spring bearing against a flange, *n*, on the outer end of the socket, and the opposite end of the spring bearing against the upright *d*, in which the tube *O* has its bearings. A pin, *o*, passes transversely through the socket *P* and through an oblong slot, *p*, in the rod *M*, as shown in fig. 1. The front end of the rod *M* is bevelled or tapered, as shown at *q*, to correspond to the flaring end *l*, of the hole *k*, and the plunger or punch *N* is of such diameter that it may work through the hole *k*. On the outer side of the plate or bar *L*, and over the hole *k*, there is secured a steel plate, *r*, having a hole, *s*, made in it to admit of the plunger or punch *N* passing through it. This perforated plate *r* serves as a cutter or shears, and admits of the plunger or punch cutting a smooth round hole through the tube or cup *h*. When the chamber *i** containing the tube or cup *h* arrives opposite the hole *k*, the plunger or punch *N* is moved forward and forces the tube or cup out from the chamber *i** into hole *k*, and cuts a hole through the outer end of the tube or cup, and the rod *M* is then moved forward and swages the inner end of the tube or cup in flaring form; the conveyer or carrier *H*, during this last operation, moving towards the plate or bar *E*, so that the chamber *i** may receive another tube or cup from the hole *g* and convey it to the hole *k* of the plate or bar *L* for the finishing operation last described. When this finishing operation is completed the plunger or punch *N* and rod *M* are drawn out from hole *k*, and the plunger or punch *N* drawn within the rod *M*, and the finished eyelet thereby discharged from the plunger or punch. In this finishing operation the eyelet is not drawn out in taper form, as is the case in a greater or less degree with eyelets manufactured with the ordinary machines in use. By my machine the eyelets are made with the metal of nearly an equal thickness throughout their entire length, the flaring end of the eyelet being upset in the flaring end *l* of the hole *k*.

Having thus described my invention, what I claim as new, and desire to secure by Letters Patent, is—

1. The combination of the sliding rod *M*, punch *N*, tube *O*, flanged socket *P*, and spring *Q*, with the finishing die *L*, substantially as described, as and for the purpose specified.
2. The conveyer or carrier *H*, provided with the chamber *i**, and arranged to operate in connection with the female dies and tubes, substantially as and for the purpose specified.

The above specification of my invention signed by me this 1st day of May, 1866.

LEVI RICHARDS.
